UNITED STATES PATENT OFFICE.

PAUL A. RAICHE, OF PROVIDENCE, RHODE ISLAND.

CAM-FORMING MACHINE.

Application filed January 16, 1924. Serial No. 686,682.

To all whom it may concern:

Be it known that I, PAUL A. RAICHE, a citizen of the United States, residing at Providence, in the county of Providence and 5 State of Rhode Island, have invented certain new and useful Improvements in Cam-Forming Machines, of which the following is a specification.

This invention relates to machines for 10 developing, laying out or forming cams, preferably the type known as edge cams such for instance those used on automatic screw machines; and the object of this invention is to provide a machine of this character 15 which is adapted to be set so that it will automatically lay out the shape of the cam on a sheet of paper, or the machine may be constructed to cut the cam in metal, if desired.

20 A further object of the invention is to provide a machine of this character having a bar adapted to be adjusted to the desired angle to obtain the relative rise of the cam, the same being adapted to be advanced at 25 a predetermined speed to impart motion due to the inclination of this bar, to a pencil which is arranged to describe the outline of the cam on the work or sheet of paper mounted on a rotatable table which is revolved at a constant speed relatively to the 30 feeding movement of the angle bar.

With these and other objects in view, the invention consists of certain novel features of construction, as will be more fully described, and particularly pointed out in the 35 appended claims.

In the accompanying drawings:

Figure 1 is a plan view of my improved developing and laying out machine.

40 Figure 2 is a section on line 2-2 of Figure 1, showing the clamping means of the angle bar.

Figure 3 is a side elevation of the machine.

45 Figure 4 is an elevation on line 4-4 of Figure 1, looking in the direction of the arrows and showing the drawing table and the worm and gear in section for rotating the same; also the segment by which the pencil is swung across the work or drawing sheet.

50 Figure 5 is a section on line 5-5 of Figure 1, looking in the direction of the arrows and showing the carriage slide bar as mounted in a dovetailed guide bar, and the angle bar as engaging the roll on the rack bar.

Figure 6 is a section on line 6-6 of Figure 1, showing the bearing on the slide bar as arranged to receive the main feed screw.

Figure 7 indicates a cam lobe and the 60 method by which it is being laid out and developed mechanically by the operation of my machine.

It is found in the laying out of cams of this character by the old method, where the combined rise and advance is laid out by hand that when the radius is swung between two definite given points, from some indefinite point which may be decided upon by the draftsman that the working face of 70 the cam lobe is usually far from being accurate and when transferred to the metal cam itself, as is the case where screw cutting cam lobes are developed for an automatic screw machine, these inaccuracies take considerable time of a skilled mechanic to correct as such cams require to be developed and cut with the greatest accuracy.

By the use of my improved machine by 75 which this cam line is laid out mechanically, I set my incline bar in a position to determine the exact height of the cam in a certain distance of travel which together with the speed of rotation of the work determines the absolute accurate curve or lead of the 80 working edge of the cam, thus obviating the necessity of subsequent re-cutting or re-shaping to obtain the accurate curve required.

85 As it is possible with my machine to make an accurate lay out of the cam on paper, it is therefore possible to transfer these lines to metal so that an accurate templet may be formed, and by the use of such a templet only the minimum amount of stock need be removed in finishing the surface in a cam-cutting machine; and the following is a detailed description of one means by 90 which these advantageous results may be accomplished:—

95 With reference to the drawings, 10 designates a base or table on which my improved cam-developing machine is mounted. The machine has a guide bar 11 preferably formed with a dovetailed groove and is secured by bolts 12 to the base or table.

100 In this guide-bar, I have mounted a slide bar 13 of corresponding dovetail shape to slide longitudinally therein. Bolted to one end of this slide bar as at 14 is the gradu-

ated arcuate segment 15 and on the opposite end of this slide bar 13 is mounted a bracket 16 in which an incline bar 17 is pivoted at 18. This incline bar is adapted to be 5 adjusted and bound in any set position along the length of the segment 15 by a clamp 19 and screw 20, see Figure 2.

In order to move this slide-bar with its inclined bar longitudinally at a predetermined, constant speed, I have mounted an 10 elongated, longitudinally-disposed screw 21 at one end in the bearing 22 and at its opposite end in the bearing 23 and a nut 24 is threaded onto this screw and connected 15 by means of the bracket 25 to the slide-bar 13, whereby the rotation of this screw is caused to move the slide bar together with its inclined bar endwise at a speed which is determined by the speed of the 20 driving motor 26 which is arranged to drive the screw through pulley 27, belt 28 and pulley 29. A handle 30 is also provided on the pulley 29 whereby the machine may be operated by hand independently of the motor, 25 when desired.

In order to lay out or develop the lead of the cam on the work which includes its rise with relation to its rotation, I have provided a turn table 31 for supporting the work or 30 sheet and which is rotated at a constant speed and in time with the rotation of the drive screw 21 through the bevel gears 32, shaft 33, spur gears 34, jack shaft 35, worm 36 and worm gear 37, which latter is mounted on and fixed to the upright shaft 38 by set screw 39 to which the table 31 is also fixed by set screw 40.

On this table, I preferably mount and 40 fix the work which in this case is a sheet of drafting paper 41 and on which paper the cam is laid out, developed or formed. By the term "work" I include either the surface on which the cam is laid out or the metal in which the cam is cut, and by "tool" 45 I mean either the point which forms the cam on the paper or the cutter which forms the cam in the metal.

In some instances, this sheet of paper may 50 be plain, or as illustrated in Figure 1, may be graduated into convenient units as occasion may require so as to visibly indicate in a general way the correctness of the work as it progresses.

In order to describe the lines on the paper 55 in the development of the cam, I have fixed a tool or pencil carrying arm 42 on an upright shaft 43 to extend over the table and on the outer end 44 of this arm is mounted a short vertical shaft 45, on the lower end 60 of which is secured a disk 46 with a tool, which in this case may be a pencil 47 or pen, mounted therein and offset from the rotating center of the disk a distance which is equivalent to the radius of the cutter which 65 will be employed in the final finishing of the

cam in metal. This pencil point is revolved about the center of this shaft by means of an electric motor 48 through a belt 49, pulley 50, belt 51 and pulley 52, to describe a multiplicity of closely formed circles as it 70 is being moved over the surface of the paper due to the combined rotation of the table and the radial rise of the pencil whereby the common tangential line of these circles indicates the working face of the cam. 75

In order to obtain the desired rise of the cam as indicated in Figure 7, by the line 63, developed by the tangent of the intersecting circles 64 described by the revolving pencil with relation to the rotation of the 80 cam, I have provided a motion-transmitting rack-bar 53 to slide endways in bearings 57, and which bar is provided with teeth 54 to engage those of segment 55 which is mounted on and fixed to shaft 43, and also on this 85 rack-bar near the opposite end, I have mounted a roll 56 which engages the adjacent edge of the incline bar 17 whereby the endways movement of the slide-bar 13 with its incline bar 17 under action of the 90 screw 21 causes the pencil 47 to be swung by the arm 42 outwardly towards the periphery of the cam, and this screw at the same time, is caused to transmit a rotating motion to the turn table 31 and its sheet 41 95 to simultaneously develop the advance of the cam line. Therefore, it will be seen by my improved construction of machine for mechanically laying out cams that the rise of the cam may be determined by the extent of inclination of the inclined bar 17 in 100 which case the pencil or tool is moved outwardly which movement cooperating with the rotation of the table serves to determine the accurate peripheral curve of the cam. 105

In forming the drop of the cam as indicated by the dotted line 62 in Figure 7, it is only necessary to remove the roll 56 from engagement with the upper edge of the incline bar and insert it in the dotted position 110 to engage the lower edge of the bar and then by reversing the direction of rotation of the main driving motor 26 and screw 21 this slide-bar 13 with its incline bar 17 is caused to move back towards the left. In 115 order that the turn table 31 shall continue to move in its original direction while the pencil driving parts are caused to move in the opposite direction, I withdraw the clutch 58 from the table driving gear train and connect the clutches 59 to drive through the reverse gears 60 and the speeding-up gears 61 the ratios of which are now arranged to increase the relative rotating speed of 120 the table 31. 125

I have shown and described my improved cam developing or forming machine as adapted to develop, form or lay out a cam by moving a tool such as a pencil or pen over the face of a sheet of paper, the ma- 130

chine being formed of a comparatively light construction to be used in a drafting room, but by making this machine heavier and positioning a cutter of the diameter of the circle described by the pencil in the pencil-head, instead of the pencil, and mounting a metal cam blank on the shaft 38, instead of the turn table 31, the cutter may take the place of the pencil and operate upon the edge 10 of the cam to form or finish the working edge of the same, and any machine of my general construction which is adapted to operate a tool to form the working face of a cam either on paper or on the metal itself, 15 will fall within the spirit and scope of this invention.

The foregoing description is directed solely towards the construction illustrated, but I desire it to be understood that I reserve 20 the privilege of resorting to all the mechanical changes to which the device is susceptible, the invention being defined and limited only by the terms of the appended claims.

25 I claim.

1. In an automatic cam-forming machine, a tool, a pivoted tool-carrying arm, means for rotating the work relatively to the tool, a traveling inclined bar adapted to be set 30 at different angles to its path of travel, a segment, a rack bar moved by said inclined bar to rotate said segment and to act upon said arm to determine the rate of movement of said arm relative to the speed of rotation of the work whereby the tool is caused 35 to develop the shape of the cam on the work.

2. In an automatic cam-forming machine, a rotatable work-carrying table, a tool, a 40 pivoted tool-carrying arm mounted to swing over said table, an endways movable slide-bar, a movable rod connected to rotate said tool arm on its pivot, an inclined bar mounted on said slide bar to move said rod, and 45 means for moving said slide bar and its inclined bar and simultaneously rotate said

table to cause the tool to develop a cam on the work.

3. In an automatic cam-forming machine, a rotatable work-carrying table, a tool, a 50 pivoted tool-carrying arm mounted to swing over said table, a slide bar, an inclined bar mounted on said slide bar to be moved longitudinally by said slide bar, means including a rack bar and segment through which 55 motion may be transmitted from said inclined bar to said tool arm, and means for rotating said work table at a predetermined speed relatively to the swinging movement 60 of said arm to cause the tool to describe a cam curve on the work.

4. In an automatic cam-forming machine, a guide frame, a slide bar in said frame, a rotatable work holder, an inclinable bar carried by said slide bar to be set at a predetermined angle to the path of travel of said slide bar, a tool arranged to operate upon the work, means for advancing the inclinable bar to move said tool over the work, and means for simultaneously rotating the 70 work at a speed relative to the advance of the inclinable bar to cause the tool to describe a cam of the desired shape on the work.

5. An automatic cam-forming machine, comprising a slide bar having a graduated arcuate segment at one end, an inclined bar pivoted at one end to said slide bar, its free end being adapted to work over said arc, a screw for feeding said slide 80 bar and inclined bar, a turn table for supporting the work, a tool, a tool-arm adapted to swing over said table and move the tool to operate upon the work, a segment, a rack bar operated by said inclined bar to move 85 said segment to swing and move its tool over the work at a speed relatively to the speed of rotation of the table to develop a cam upon the work.

In testimony whereof I affix my signature.

PAUL A. RAICHE.
